UNITED STATES PATENT OFFICE.

AARON BLUME, OF NEW YORK, N. Y.

SMOKING AND PLAYING CARD COMPACT.

Application filed July 20, 1927. Serial No. 207,136.

My invention relates to cabinets adapted to contain cigars, cigarettes, matches, playing cards, score cards, pencils and the like, and it is my object to produce a compact cabinet

5 in which the various articles may be conveniently stored and from which they may be taken as desired, the cigars or cigarettes being automatically extracted, one by one. A further object is the construction of 10 the cabinet in a simple and cheaply produced form, free from mechanical complications, which might get out of order.

In the drawing Fig. 1 is a view of my cabinet with the drawer open, showing an 15 extracted cigarette, the accessible matches and a partly extracted cigar; Fig. 2 a top view of the cabinet of Fig. 1 with the lid opened; Fig. 3 a sectional view of the structure of Fig. 2 on the line 3—3 thereof; Fig. 20 4 a sectional view of the structure of Fig. 2 on the line 4—4 thereof; Fig. 5 a sectional view of the structure of Fig. 2 on the line 5—5 thereof; Fig. 6 a top view of the drawer; and Fig. 7 a side view of the drawer.

25 The cabinet 1 is provided with a lid 2. An ash tray 3 may be secured to the cabinet in any suitable manner.

The bottom of the front of the cabinet is provided with an opening to receive a 30 drawer 4, which holds the matches and forms the cigarette extracting mechanism.

As best shown in Figs. 6 and 7 this drawer consists of a bottom 5, which substantially covers the bottom of the cabinet, with compartments 6 and 7 at the front. The compartment 6 is apertured at 8 to expose the striking surface of a match box cover contained therein. The compartment 7 contains the matches. This drawer 4 has a front, 40 forming one wall of the compartments above described, and but one side 9 which is stepped up from 10 to 10' and has a groove 11 running along its upper edge.

In making the compartments for the inside of the cabinet I take a long strip of sheet metal and bend it on itself so that a vertical wall 12, a horizontal wall 13, a back wall 14, a second horizontal wall 15, provided with apertures as shown in Figs. 2, 4 and 50 5, a vertical wall 16—17, a horizontal wall 18, provided with a slot, a vertical wall 19—20, a second horizontal, slotted wall 21, a vertical wall 22 and finally a horizontal wall 23 which is secured to the wall 12, is formed. 55 All the horizontal walls are located above

the bottom of the cabinet so that the drawer may slide freely under them. This compartment unit may be slid into place in the cabinet.

A partition 24 is secured inside the cabinet and spaced sufficiently from the side wall to form cigarette pockets and for the drawer side 9 to slide in.

When the sheet metal partition unit is slid into the cabinet it divides it into a large 65 compartment *a* which is adapted to hold packs of playing cards which are slipped through the apertures 25 and 26 in the partition 15 and rest on the partition 13. An aperture 27 may be likewise provided for the score 70 cards and a pencil clip 28 may be secured inside the cabinet.

The compartments *b* and *c* are adapted to hold cigars laid horizontally one on top of another. An opening 29 is cut in the side 75 of the cabinet, alining with the cigar compartment, and is closed by a swinging cover 30.

To extract a cigar a plunger 31 passes through the side of the box into the space between the partitions 21, 18, 22, 23 and 12, which form a guideway for the plunger. An extractor extension 32 passes into the bottom of the compartment *c* through a slot 33 in the bottom thereof. When the plunger 31 is 85 pulled out the bottom cigar will be drawn out through the cover 30, the upper edge of the extractor 32 holding the pile of cigars above the bottom. When the plunger is pushed in the extractor 32 will clear the piled cigars at their inner end and they will fall to the bottom of the compartment ready to extract the bottom one. The length of the slot 33 determines the travel of the plunger. To hold the cigars above the bottom one in position to allow the 90 extractor 32 to operate a sloping end 24' is provided for the compartment which does not reach to the bottom and under which the extractor normally rests. The extracting mechanism is duplicated in compartment *b*.

To extract cigarettes the drawer is simply pulled out. When the drawer is in place in the bottom of the cabinet the edge of the drawer side 9 is under the cigarette compartment *d*, in which the cigarettes are laid horizontally one on top of another, with the bottom one in the groove in the top edge 10. When the drawer is pulled forward the bottom cigarette will travel forward with the drawer and the raised part 10' will travel un- 105 110

der the piled cigarettes and hold them up. The extracted cigarette may then be picked up. When the drawer is closed the bottom cigarette will fall into the groove 10 ready for extraction on another opening of the drawer. A reserve supply of cigarettes may be placed vertically in the compartment *e* in the rear of the extractor compartment.

If a match only is wanted the drawer may be opened sufficiently to obtain it without opening it far enough to extract a cigarette.

By this construction I am able to produce a complete, compact cabinet for smokers and card players which is self contained and in which the mechanism is so simple that it will work unfailingly and cannot get out of order.

If desired suitable absorbent material may be placed in the cabinet, such as is indicated

between the walls 24 and 24' in Fig. 3, to hold moisture to prevent the tobacco drying out. 20

I claim:—

As a new article of manufacture, a smoking and playing card compact comprising a cabinet, a compartment in said cabinet adapted to contain horizontally arranged cigarettes one 25 above another, a drawer consisting of a bottom a front wall and a stepped side wall up-standing therefrom slidable in said cabinet, the stepped side on said drawer travelling under said compartment whereby cigarettes or 30 the like will be extracted on opening the drawer.

In testimony whereof I have affixed my signature.

AARON BLUME.
